(57) **CLAIM**

The ornamental design for a chain with foldable glasses, as shown and described.

DESCRIPTION

FIG. 1 is an isometric view of a first embodiment of our new design in the folded configuration with only a portion of the chain shown.

FIG. 2 is a front view of a first embodiment of our new design in the folded configuration with only a portion of the chain shown.

FIG. 3 is a left side view of a first embodiment of our new design in the folded configuration with only a portion of the chain shown.

FIG. 4 is a rear view of a first embodiment of our new design in the folded configuration with only a portion of the chain shown.

FIG. 5 is a right side view of a first embodiment of our new design in the folded configuration with only a portion of the chain shown.

FIG. 6 is a top view of a first embodiment of our new design in the folded configuration with only a portion of the chain shown.

FIG. 7 is a bottom view of a first embodiment of our new design in the folded configuration with only a portion of the chain shown.

FIG. 8 is an isometric view of a first embodiment of our new design in the unfolded configuration with only a portion of the chain shown.

FIG. 9 is a front view of a first embodiment of our new design in the unfolded configuration with only a portion of the chain shown.

FIG. 10 is a left side view of a first embodiment of our new design in the unfolded configuration with only a portion of the chain shown.

FIG. 11 is a rear view of a first embodiment of our new design in the unfolded configuration with only a portion of the chain shown.

FIG. 12 is a right side view of a first embodiment of our new design in the unfolded configuration with only a portion of the chain shown.

FIG. 13 is a top view of a first embodiment of our new design in the unfolded configuration with only a portion of the chain shown.

(Continued)

FIG. 14 is a bottom view of a first embodiment of our new design in the unfolded configuration with only a portion of the chain shown.

FIG. 15 is an isometric view of a second embodiment of our new design in the folded configuration with only a portion of the chain shown.

FIG. 16 is a front view of a second embodiment of our new design in the folded configuration with only a portion of the chain shown.

FIG. 17 is a left side view of a second embodiment of our new design in the folded configuration with only a portion of the chain shown.

FIG. 18 is a rear view of a second embodiment of our new design in the folded configuration with only a portion of the chain shown.

FIG. 19 is a right side view of a second embodiment of our new design in the folded configuration with only a portion of the chain shown.

FIG. 20 is a top view of a second embodiment of our new design in the folded configuration with only a portion of the chain shown.

FIG. 21 is a bottom view of a second embodiment of our new design in the folded configuration with only a portion of the chain shown.

FIG. 22 is an isometric view of a second embodiment of our new design in the unfolded configuration with only a portion of the chain shown.

FIG. 23 is a front view of a second embodiment of our new design in the unfolded configuration with only a portion of the chain shown.

FIG. 24 is a left side view of a second embodiment of our new design in the unfolded configuration with only a portion of the chain shown.

FIG. 25 is a rear view of a second embodiment of our new design in the unfolded configuration with only a portion of the chain shown.

FIG. 26 is a right side view of a second embodiment of our new design in the unfolded configuration with only a portion of the chain shown.

FIG. 27 is a top view of a second embodiment of our new design in the unfolded configuration with only a portion of the chain shown; and,

FIG. 28 is a bottom view of a second embodiment of our new design in the unfolded configuration with only a portion of the chain shown.
